[57] CLAIM

The ornamental design for a self-retracting, wall-mounted desk and chart holder, as shown and described.

DESCRIPTION

FIG. 1 is a perspective view of the self-retracting, wall-mounted desk and chart holder, illustrating the desktop in the vertically closed position;

FIG. 2 is a front elevational view of the self-retracting, wall-mounted desk and chart holder, illustrating the desktop in the vertically closed position;

FIG. 3 is a right side elevational view of the self-retracting, wall-mounted desk and chart holder, illustrating the desktop in the vertically closed position;

FIG. 4 is a top view of the self-retracting, wall-mounted desk and chart holder, illustrating the desktop in the vertically closed position;

FIG. 5 is a rear elevational view of the self-retracting, wall-mounted desk and chart holder, illustrating the desktop in the vertically closed position;

FIG. 6 is a left side elevational view of the self-retracting, wall-mounted desk and chart holder, illustrating the desktop in the vertically closed position;

FIG. 7 is a bottom view of the self-retracting, wall-mounted desk and chart holder, illustrating the desktop in the vertically closed position;

FIG. 8 is a perspective view of the self-retracting, wall-mounted desk and chart holder, illustrating the desktop in the horizontally open-use position;

FIG. 9 is a top view of the self-retracting, wall-mounted desk and chart holder, illustrating the desktop in the horizontally open-use position;

FIG. 10 is a front elevational view of the self-retracting, wall-mounted desk and chart holder, illustrating the desktop in the horizontally open-use position;

FIG. 11 is a bottom view of the self-retracting, wall-mounted desk and chart holder, illustrating the desktop in the horizontally open-use position;

FIG. 12 is a right side elevational view of the self-retracting, wall-mounted desk and chart holder, illustrating the desktop in the horizontally open-use position;

FIG. 13 is a left side elevational view of the self-retracting, wall-mounted desk and chart holder, illustrating the desktop in the horizontally open-use position;

FIG. 14 is a rear elevational view of the self-retracting, wall-mounted desk and chart holder, illustrating the desktop in the horizontally open-use position;

FIG. 15 is a rear perspective view of the self-retracting, wall-mounted desk and chart holder, illustrating the desktop in the horizontally open use position; and,

FIG. 16 is a rear perspective view of the self-retracting, wall-mounted desk and chart holder, illustrating the desktop in the vertically closed position.
